(57) **CLAIM**

The ornamental design for an automobile hood, as shown and described.

DESCRIPTION

FIG. 1 is a perspective of an automobile hood as seen from the front right showing my new design;

FIG. 2 is a front view thereof;

FIG. 3 is a right side view thereof, the left side being a mirror image thereof;

FIG. 4 is a rear view thereof; and,

FIG. 5 is a top view thereof.

The broken lines in the drawings mark boundaries which form no part of the claimed design. The broken lines in FIG. 2 mark the boundary of an area in which a grill may be mounted. The marked area and the grill do not form a part of the claimed design.

The bottom of the automobile hood does not form a part of the claimed design.
